UNITED STATES PATENT OFFICE.

WILLIAM C. FORSEE, OF KANSAS CITY, MISSOURI.

WASHING APPARATUS.

1,271,025.

Specification of Letters Patent. Patented July 2, 1918.

Application filed December 3, 1917. Serial No. 205,189.

To all whom it may concern:

Be it known that I, WILLIAM C. FORSEE, a citizen of the United States, residing at Kansas City, in the county of Jackson and 5 State of Missouri, have invented certain new and useful Improvements in Washing Apparatus; and I do declare the following to be a full, clear, and exact description of the invention, such as will enable others skilled 10 in the art to which it appertains to make and use the same.

My invention has for its object to provide an extremely simple and inexpensive, yet a highly efficient apparatus for washing 15 clothes or other articles, it being my intention to provide means for intermittently forcing a blast of steam and scalding water upwardly through the articles in the washing receptacle, the hot water returning to 20 its previous level after each blast.

With the foregoing general object in view, the invention resides in the novel features of construction and unique combinations of parts hereinafter fully described 25 and claimed.

In the drawings, a vertical section of the improved washing apparatus is shown.

The numeral 1 designates a boiler whose 30 wall 2 is increased in diameter at its upper end as shown at 3, a downwardly and inwardly inclined ledge 4 being formed at the juncture of the two diameters. The upper side of the ledge 4 is provided with a suitable water seal trough 5 in which is received 35 the depending flange 6 of an inclined cover 7, the highest point of said cover having steam outlet perforations 8 which discharge into the space surrounded by a continuous wall 9 which rises from the cover, said wall 40 also having outlet perforations 10. A horizontal partition 11 is provided in the wall 9 and supports a weight 12 which normally holds the cover 7 down in place, but when the pressure beneath this cover rises suf- 45 ficiently to overcome the weight of the cover and weight 12, said cover will automatically raise to permit the escape of steam and water as hereinafter set forth. A cap 13 is positioned over the wall 9, the flange 14 of 50 said cap having its lower edge flared as shown at 15 and positioned opposite the perforations 10. By this arrangement, the flared edge 15 constitutes steam retarding means, so that a quantity of the steam will 55 be caused to condense and drip onto the

cover 7, from which it will trickle into the trough 5.

Positioned in the boiler 1, is a receptacle 16 for the articles to be washed, the wall 17 and the bottom 18 of said receptacle being 60 spaced from the wall and bottom of the boiler 1. The upper edge of wall 17 is turned outwardly at 19; and secured in any suitable steam tight manner to the wall 2 of the boiler 1 whereby a continuous steam 65 dome 20 is provided between the walls of the receptacle 16 and the boiler 1. This dome is without communication with the interior of the receptacle 16, except through a 70 passage 21 in the form of a short tube or the like depending from the bottom 18 into the boiler. The dome 20, however, may be placed in communication with the atmosphere, whenever required, by means of a suitable vent or valve 22 at the upper end 75 thereof.

The bottom 18 is provided with a grating 23 spaced above the same to support the articles to be washed, and a similar grating 24 is supported upon suitable ledges 24', 80 substantially midway the upper and lower ends of the receptacle 16, said last named grating serving to divide the receptacle into two compartments for the soiled articles. These articles are held within the upper 85 compartment by a third grating 25 which may well rest upon the outwardly turned upper end of the receptacle 16. The two grates 24 and 25 are held removably in place by suitable spring catches or the like such 90 as those indicated at 26 in the drawing.

In operation, the entire device is supported above a suitable heater 27 which may well be one of the burners of an ordinary gas stove. The receptacle 16 is now filled with 95 the articles to be cleaned and the gratings 24 and 25 are secured in place. By pouring a sufficient quantity of water into the receptacle 16, with the vent 22 opened, both said receptacle and the boiler 1 will be filled 100 to the required extent, preferably as shown in the drawing. The vent 22 is now closed and the cover 7 applied. If required, water may be poured into the trough 5 to seal the latter, but in most cases this is unnecessary, 105 since the water of condensation on the inner side of the inclined cover 7, will trickle downwardly along this cover and will soon accumulate in sufficient quantity in the trough 5 to form an effective water seal. 110

As the water boils, steam will accumulate in the dome 20 so that the water level within the boiler is gradually forced downwardly, whereas that in the receptacle 16 is correspondingly raised. When the level in the boiler has been thus forced downwardly to a sufficient extent, the generation of steam under pressure is rapid, with the result that as this accumulating body of steam increases in power, it will suddenly overcome the resistance of the water and will violently expand, so that a mixture of steam and scalding water is discharged into the receptacle 16 through tube 21, in an extremely strong blast. This mixture of scalding water and steam rushes upwardly through the articles in the receptacle 16 and thus performs an effective cleaning operation thereon. When this upward rush takes place, the water will pass out under flange 6 and will rise within the enlarged upper end of wall 2, partly covering the top 7. The water is thus cooled slightly and this cooling, together with the partial vacuum formed in boiler 20 by the outrush of water and steam, will cause the water to again lower and remain until the next impulse of steam is released. Any escaping steam from perforations 10 during the operation of the device, strikes the baffle 15 and is partially condensed, so that the water of condensation drips onto the cover 7 and trickles along the latter into the trough 5. If the latter overflows, the water therefrom will be returned to the receptacle 16, so that little loss occurs.

The outrush of water and steam beneath flange 6 is expedited by the fact that the internal pressure then overcomes the weight of the cover 7 and the weight 12, so that said cover lifts slightly from the trough 5.

As the water seeks its previous level, it must pass downwardly through the articles. Here again, an effective cleaning is exerted. In short, the apparatus successively forces strong blasts of steam and water upwardly through the articles and between said blasts, causing a downward flow of hot water therethrough. Excellent results are thus obtained.

I am aware that clothes steaming devices somewhat resembling the present invention, in appearance, have heretofore been devised, but in all of such apparatuses, some constant means of communication between the steam dome and the receptacle for the soiled articles is provided. I employ no such constant means of communication and thus the action of the apparatus is changed entirely for the better.

From the foregoing, taken in connection with the accompanying drawings, it will be obvious that although my invention is of extremely simple and inexpensive nature, it will be highly efficient and durable. For these reasons, the several specific details

shown and described are preferably employed, but I wish it understood that within the scope of the invention as claimed, numerous minor changes and additions may well be made. For instance, the wall 2 of the boiler 1 may be provided with a number of openings having removable closures 28, whereby the hand and arm may be inserted to clean the dome 20 whenever necessary. Thus, deposits which might otherwise impair the efficiency of the apparatus, are prevented from accumulating.

I claim:

1. A washing apparatus comprising a receptacle for the soiled articles, a steam-tight water boiler in which the steam is trapped as it is generated, and a water sealed passage for automatically supplying an impulse of steam under pressure to said receptacle whenever sufficient steam pressure has been generated in the boiler to overcome the resistance of the water.

2. A washing apparatus comprising a water boiler, a receptacle in said boiler for the soiled articles, the bottom and wall of said receptacle being spaced from the bottom and wall of said boiler, the space between the upper ends of the two walls being sealed in a steam-tight manner and the upper portions of said boiler and receptacle forming a sealed chamber for supplying an impulse of steam to said receptacle when sufficient steam pressure has been generated in said boiler to overcome the resistance of the water, said receptacle having means communicating with said sealed chamber and through which said impulse of steam takes place.

3. A washing apparatus comprising a water boiler, a receptacle in said boiler for the soiled articles, the bottom and wall of said receptacle being spaced from the bottom and wall of said boiler, the space between the upper ends of the two walls being sealed in a steam-tight manner and the upper portions of said boiler and receptacle having no means of communication, the lower end of said receptacle having a passage for supplying an impulse of steam to said receptacle when sufficient steam pressure has been generated in said boiler to overcome the resistance of the water, a continuous water seal trough adjacent the upper end of said receptacle, the wall of said boiler extending above said trough, and a cover having a depending continuous flange extending into said trough.

4. A washing apparatus comprising a water boiler, a receptacle in said boiler for the soiled articles, the bottom and wall of said receptacle being spaced from the bottom and wall of said boiler, the space between the upper ends of the two walls being sealed in a steam-tight manner and the upper portions of said boiler and receptacle having no

means of communication, the lower end of said receptacle having a passage for supplying an impulse of steam to said receptacle when sufficient steam pressure has been generated in said boiler to overcome the resistance of the water, a continuous water seal trough adjacent the upper end of said receptacle, the wall of said boiler extending above said trough, an inclined cover having a continuous depending flange extending into said trough, a steam vent rising from said cover and having outlet perforations opening laterally, and steam retarding means spaced outwardly from said perforations for causing partial condensation of escaping steam, whereby the water of condensation will drip onto said inclined cover and trickle into said trough.

5. In a washing machine, the combination with an inclined cover of a washing chamber in which steam is housed, and a water seal at the edge of said cover, of a continuous

wall rising from a high point of said cover, the latter having a steam outlet into the space surrounded by said wall and 25 said wall having outlet perforations, a partition across said wall above said outlet perforations, a weight on said partition to hold said cover engaged with said water seal, and a cap fitting over said wall and 30 having the lower edge of its flange flared and disposed opposite the perforations of said wall to form means for partly condensing the steam escaping and causing the water of condensation to drip onto said top, from 35 which it may trickle into said water seal.

In testimony whereof I have hereunto set my hand in the presence of two subscribing witnesses.

WILLIAM C. FORSEE.
